CLAIM

I claim the ornamental design for a single X-frame grill cart, as shown and described.

DESCRIPTION

FIG. 1 is a perspective view of a single shelf X-frame grill cart showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The kettle and ash can shown in broken lines in FIG. 1, form no part of the claimed design.

1 Claim, 4 Drawing Sheets
